UNITED STATES PATENT OFFICE.

JOHN R. GOLDEN, OF HAMMOND, INDIANA.

AUTOMATIC RAILROAD-CROSSING GATE.

Application filed April 7, 1919. Serial No. 288,027.

To all whom it may concern:

Be it known that I, JOHN R. GOLDEN, a citizen of the United States, and a resident of the city of Hammond, county of Lake, and State of Indiana, have invented certain new and useful Improvements in Automatic Railroad-Crossing Gates, of which the following is a specification.

My invention relates to improvements in automatic railroad crossing gates and has for its object the provision of a device which will automatically lower the gates at a railroad crossing upon the approach of a train thereto, and automatically raise the same after the train has passed. Another object is the provision of a railroad crossing gate, electrically connected with a device, upon the passing over of which by a train the gate will be lowered as the train approaches the crossing, and raised after the train has passed the crossing.

Other objects will appear hereinafter.

The invention consists in the combinations and arrangements of parts hereinafter described and claimed.

The invention will be best understood by reference to the accompanying drawings forming a part of this specification, and in which,

Fig. 1, is a top plan view of the device applied,

Fig. 2, is a side elevation of the gate-operating mechanism,

Fig. 3, is a front elevation of the gate-operating mechanism,

Fig. 4, is a rear elevation of the gate-operating mechanism,

Fig. 5, is a side elevation of an exhaust valve,

Fig. 6, is a longitudinal sectional view of the exhaust valve,

Fig. 7, is a top plan view of the circuit breaker,

Fig. 8, is a front elevation of part of the gate-operating mechanism,

Fig. 9, is a fragmental sectional view of part of the gate-operating mechanism,

Fig. 10, is a perspective view of a valve,

Fig. 11, is a sectional view of the valve taken on lines 11—11 of Fig. 1,

Fig. 12, is a sectional view of the valve taken on line 12—12 of Fig. 1,

Fig. 13, is a sectional view of the valve taken on line 13—13 of Fig. 1,

Fig. 14, is a sectional view of Fig. 8 taken on line 14—14 of Fig. 1,

Fig. 15, is a top plan view of the electrical device, with the housing top removed,

Fig. 16, is a side elevation of one electrical device with the wall of the housing and parts 60 removed,

Fig. 17, is a section taken on line 17—17 of Fig. 16,

Fig. 18, is a sectional view taken on line 18—18 of Fig. 16, and

Fig. 19, is a sectional view taken on line 19—19 of Fig. 16.

In the operation of the device, there is stationed, in close proximity to the railroad crossing gate, an electrically operated mechanism which in turn operates an air pressure mechanism for raising or lowering the gate. Stationed along the railroad track, on both sides of the gate, are electrical devices, which are adapted to break and close an electric circuit upon the passing of a train along the track at the point where these devices are stationed.

The preferred form of construction, as illustrated in the drawings, comprises a 80 housing 19 enclosing a shaft 20 mounted on suitable bearings 20' and 20'' secured to the base of housing 19, one end of said shaft projecting through one side of said housing. Secured to the end of the shaft which projects through the housing 19 is an upright arm 21 adjacent to and projecting above the rail 22, so that a wheel, in passing along said rail, will strike the arm 21 and oscillate it. At the opposite end of said shaft, enclosed 90 within the housing, is secured a perpendicularly extending arm 23 having a horizontally projecting portion 24. Pivots secured to lugs 25, projecting from the base of said housing, adjacent to and opposite the arm 23, is a four-blade knife switch, having the blades 27 connected at their upper end by an insulating member 28 from the center of which upwardly projects an insulating stud 29 which loosely engages in a slot 30 in 100 the member 24, so that upon the rocking of the member 24 in either direction the blades 27 will be carried in the same direction.

Pivots mounted in the housing 19 in lugs arising from metallic members 31', 32', 105 33', 34', 35' and 36', respectively, are contact elements, also metallic, 31, 32, 33, 34, 35 and 36, so positioned that upon the rocking of the blades 27 in one direction, three of said blades will come into contact with and 110 be engaged by elements 31, 32 and 33, and upon rocking the blades 27 in the other di-

rection three of the blades will come into contact with and be engaged by elements 34, 35 and 36, the blade not coming into contact or engagement upon said rocking motion being different, according to the direction in which said blades move, as will be readily understood and as is clearly shown in Fig. 15.

Projecting from the members 31, 32, 33, 34, 35 and 36 are tails 31" having a slot, through which project studs 32", which arise from an insulating member 35" which covers the base of housing 19. Interposed between the tails 31" and the lug bearing member which co-operates with the part from which the member 31" projects, are positioned coil springs 34". Co-operating with the studs 32" are nuts 33" which serve to retain the members 31" in their position on said studs 32". As will be described later on, the blades 27, being rocked to either side, are sometimes so rocked with great force and rapidity. Upon being rocked to either side, the blades, in engaging with the elements 31, 32 and 33, and 34, 35 and 36 would come into contact with these elements with great force. Were these elements rigidly fastened, in a short time, the blades rocking against said elements would themselves, in a short time, become distorted or worn out, or would cause these elements to become distorted, loosened or worn out. Consequently, these elements are pivotally mounted and have shock-absorbing elements in the nature of spiral springs 34", which serve to assure a connection of all the blades with their corresponding elements upon a rocking motion, and which serve also to take up the shock naturally incident to these blades coming into contact with their co-operating elements, as will be readily understood.

Mounted on said shaft 20, intermediate the ends thereof, is a horizontally extending bar 37, having flanges 38 and 38' on opposite ends. Projecting through a slot in each of said flanges are posts 39 and 39' secured to the insulating member which covers the base of the housing 19 and threaded at their upper end. These posts have a nut 40 which co-operates with their threaded end, and a washer 41. Interposed between said flange and said washer, on said posts 39 and 39', are spiral springs 42, of equal tension. It is thus seen that upon pressing one end of the member 37 downwardly, the spiral tension at the opposite end of this member will tend to restore the member 37 to its horizontal position. Secured to each end of member 37, adjacent the axis thereof, are metallic spring contact members 43, as clearly seen in Fig. 15. Mounted in the housing 19, on opposite sides of the shaft and adjacent the members 43, are magnetic coils 44, an insulated member 45 being dis-

posed on shaft 20 between the coils and bearing terminals 46. Terminal posts also arise from the members 31', 32', 33', 34', 35' and 36'.

Stationed near the railroad crossing, mounted on a frame 47, is a motor 48 having a pinion or gear wheel 49 secured to the outer end of its shaft. The gear 49 meshes with the gear wheel 50, which is mounted on a shaft 51 supported in suitable bearings 52 on frame 47. The outer end of shaft 51 bears a pinion or gear wheel 53, which meshes with a gear wheel 54 mounted on a shaft 55, supported in a suitable bearing 56 on frame 47. Mounted on the side of the periphery of member 54 is a segmental gear 57. Mounted on one end of a shaft 58 supported in suitable bearings 59 on frame 47, in front of and adapted for engagement with segmental gear 57, is a gear wheel 60. Mounted on the opposite end of shaft 58 is an eccentric wheel 61 bearing the customary eccentric strap 62 and eccentric bar 63.

Rigidly mounted to the base of the member which forms the bearings 59, by means of upright bars 64', is a switch-board 64 on which is mounted a knife blade switch, each of the blades of said switch being mounted pivotally, intermediate their ends on lugs 65 which project from said switch-board. The upper ends of said knife blades are connected by an insulating member, from the center of which projects an insulated handle 66 having a slot 67 in which operates a bolt loosely connecting the arm 68 to the member 66. The arm 68 projects from a transverse bar 69 to which is secured, at one end, an arm 70 to which is pivotally connected eccentric bar 63. The bar 69 is mounted transversely at the upper end of the switch-board, in suitable bearings secured to said switch-board. The arrangement of these parts is such that upon rotation of the wheel 60, the eccentric bar is moved vertically up and down.

The connection of the eccentric bar with the knife blade switch is such that upon the upward motion of said bar, the lower ends of the blades contact with terminal elements and serve to close a switch. Upon the downward movement of said bar, the contact of the lower ends of said blades is broken and a connection is formed between the upper ends of said blades and terminal elements, thereby closing a switch at the upper ends of said blades. Secured to the outer face of the eccentric wheel, or made integral therewith, is a disc 71, so positioned on said eccentric as to be concentric with the shaft 58. Eccentrically connected to said disc 71, at one end thereof, by a pivotal connection, is a bar 72 pivotally connected at its opposite end to an arm 73 projecting laterally from a valve 74, as clearly shown in Fig. 2.

The valve 74, which is tapering or conical

shaped, as clearly seen in Fig. 10, is provided with posts 75 and 75' projecting from opposite ends. The post 75' which projects from the tapered end of the valve is threaded on its outer end. The valve seats in a housing 76, communicating with the interior of which is a feed pipe 77 and delivery pipes 78 and 79, as clearly shown in Figs. 3 and 11. An exhaust pipe 80 is connected with the feed pipe 77.

Secured to the shaft 51, opposite the end to which wheel 50 is secured, is a disc 81 to which is eccentrically pivotally mounted a piston rod 82, secured to which is a piston 83 which is mounted in a cylinder of one of the usual types of air pumps. Feed pipe 77 communicates with the interior of this cylinder, and when the pump is in operation, supplies air under pressure to the valve 74 housing and the valve, as will be readily understood. The valve 74 is retained in position in the housing 76 by means of a coil spring 84 positioned loosely on post 75' and interposed between the housing 76 and a washer which is retained in position on the outer end of post 75' by a co-operating nut, as clearly shown in Fig. 3. As is apparent, the tension of the coil spring is increased or diminished upon the turning of said nut either on or off. Provided on the outer surface of valve 74 is an L-shaped groove 85, on opposite sides of which are openings 86 and 87 which pass through the valve.

Stationed in close proximity to the valve 74 and its co-operating parts is a crossing gate 88, at the base of which is arranged suitable apparatus for raising and lowering said gate through the medium of compressed air. In this apparatus are two cylinders 89 and 89', one adapted to co-operate in lowering said gate and the other adapted to co-operate in raising the same. From the arrangement of the various elements thus far described, it is apparent that upon the starting of the motor 48, the wheel 50 will be caused to rotate and the piston 83 will be set in motion, forcing air through the feed pipe 77 and into the valve 74. The arrangement of the groove 85 is such that when the stem of the L-shaped groove is aligned or registers with the mouth of the delivery pipe 78, the base or short portion of the L-shaped groove will be aligned or register with the mouth of the feed pipe 77 so that the air forced through the feed pipe 77 will pass into the valve housing, along the L-shaped groove on the valve and out of the valve casing into delivery pipe 78, which conducts the air to the cylinder 89' of the gate raising apparatus. This will result in lowering the gate and forcing the piston in cylinder 89 up. The air in the cylinder 89 will consequently be forced back through delivery pipe 79, but at the time the air is

being forced through delivery pipe 78, as already described, the opening 87 registers with the end of delivery pipe 79. At the same time, an outlet port in the housing 76 registers with the opening 87, thereby allowing the air, which is forced back through the delivery pipe, free passage to escape. This operation takes place when the motor 48 is started while the eccentric rod 63 is in the position shown in Fig. 9. In other words, while the circuit is closed with the lower ends of the knife blades which are pivoted to members 65, the air delivered from the air pump serves to lower the crossing gate. While this operation is taking place, that is, while the air pump is in operation, the gear wheel 50 is rotated and the segmental gear 57 is brought around to a position to mesh with the gear wheel 60, thereby rotating the same. This rotation of the wheel 60 causes the eccentric bar 63 to move downwardly, breaking the connection at the lower ends of the blades of the switch and closing the circuit by means of the upper end of the blades of the switch. At the same time, the bar 72 is moved backward, thereby moving the groove 85 from alignment with the mouth of the delivery pipe 78, and consequently closing the valve at the mouth of the delivery pipe 78. The gear 57 is of such length as to rotate the gear 60 one-half of a revolution. The valve 74 is then in such a position that the mouth of the feed pipe 77 is aligned or registers with the elongated portion of the L-shaped groove, and the mouth of the delivery pipe 79 is also aligned or registers with the same portion of this groove. Upon the starting of the motor 48, the air is similarly delivered through the feed pipe into the valve housing, and out through the pipe 79 into the cylinder 89 of the gate-raising apparatus. This will force the piston in cylinder 89 up, with the consequent raising of the gate 88, at the same time forcing the piston of the cylinder 89' down, thereby forcing the air in cylinder 89 back through delivery pipe 78. The valve, in being turned as above described, will cause the opening 86 in the valve to register with the mouth of the delivery pipe 79. At this position, registering with the opening 86 in the valve is an opening in the housing, thereby affording free passage out of the valve housing to the air which is forced back through the delivery pipe 79. In the operation described above, the gear wheel makes another revolution actuating the gear wheel 60, thereby moving the valve 74 to its original position and also breaking the circuit formed by the upper end of the blades of the switch and closing the circuit by means of the lower ends of the blades of the switch. It is thus seen that this is the normal position of the valve and switch when inoperative, as the

gates 80 are normally in a raised position.

To the exhaust pipe 80 is secured a valve housing 90, in which is seated a tapering conical shaped valve 91. Projecting from 5 opposite ends of said valve are posts, one of which is threaded and adapted to receive a nut 92 and washer 92', as clearly seen in Figs. 5 and 6. The nut 92 being threaded on the valve, the latter is secured in the 10 housing under the tension of the coil spring. To the opposite side of said valve is secured a disc or drum 93 having two upwardly projecting shoulders 94 and 94'. Positioned adjacent the lower end of housing 90, secured to exhaust pipe 80, is a collar 95 having an outwardly projecting arm 95' to which is secured, at one end, a spiral spring 95'', the opposite end of said spring being secured to a stud 95''' eccentrically 15 positioned on the outer face of drum 93. On the housing 90 is positioned a stop 95'''' adapted to engage with shoulder 94'. Secured to the shaft 55 is a collar 96 having a shoulder 97 which is inclined at one end 20 and which is adapted, upon the rotation of said collar 96, to come into contact with a circuit breaker 113, to be described hereafter, which is mounted on and insulated from the bearing 56. Mounted on the shaft 25 55 is also a collar 99, having a shoulder 99' adapted, upon the rotation of the shaft 55, to engage with the shoulder 94 and thereby turn the valve 91 in the housing 90. Passing through the valve 90 is an opening 35 101 adapted to register, upon the turning of said valve, with openings 102 and 102', which communicate respectively with the outside air and the interior of exhaust pipe 80. It is thus seen, that upon rotation 40 of the shaft 55, the valve 91 is turned so as to allow the air in the tube 80 to escape. When the collar 99 is rotated sufficiently to disengage shoulder 99' from shoulder 94, the spring 95'' will serve to restore the 45 valve to its former or closed position. Shoulder 95'''' serves as a stop by engaging with shoulder 94' when the spring 95'' restores the valve to its closed position. The shoulder 99 is so positioned on the shaft 55 50 that upon rotation of the wheel 54, the exhaust valve 91 is opened to allow the escape of the air remaining in the air pump cylinder and in the pipes 77 and 80, to escape at the same time that valve 74 is operated by the eccentric rod 63. It is thus seen that 55 the movements are all synchronous relatively to each other.

In Fig. 2 the shoulder 99' is shown as having just been freed from engagement 60 with the shoulder 94, and the valve is shown in a closed condition, having been restored to its closed or normal condition by the coil spring 95''.

Secured to the bearing 56 is a make and 65 break device 113 embodying a metal spring

element 109 which is secured in position at one end by a threaded bolt 110 which passes through an insulating member 114 and contacts with the terminal post, as shown in Fig. 7. The element 109 contacts, at its opposite end, with another bolt which projects through the insulating member 114 and contacts with the terminal pole, as shown. Securely connected with the loose end of member 109 is an L-shaped member 111, which 70 projects forwardly and comes into contact with element 97 upon rotation of the wheel 54. A guide arm 98 engages with the outer end of member 111 and is adapted to prevent the outer end of member 111 from lateral movement. The member 97 being beveled or inclined at one end, upon the rotation of the wheel 54 the member 97 comes into contact with member 98 and thereby forces the member 111 outwardly. This 75 member 111 carries with it a member 109, and consequently breaks the connection which exists between the two terminal poles, as shown in Fig. 7. As is clearly seen in Fig. 4, the wire 103^a connects with each of 80 these terminal poles, each of said poles being interposed in the wire 103^a between the switch and the motor. Consequently, upon the pressing outward of the member 109 from engagement or contact with the bolt 95 which is opposite and corresponds to the bolt 110, the circuit connecting the motor is broken.

As shown in Fig. 15 the contacts 34' in the opposite housings 19 are connected by 100 a wire 103^a; the contacts 36' are connected by a wire 103^b; the contacts 31' are connected by a wire 103^c; and the contacts 33' are connected by a wire 103^d. The blades of the switches between the contacts 31' and 105 34' in the respective housings are connected by a wire 104^a; and the blades of the switches between the contacts 33' and 36' in the respective housings are connected by a wire 104^b. The wire 103^a is connected to an outside terminal post on the lower end of the switch-board 64 by a wire 103^e, and the wire 103^b is connected to the opposite outside terminal of the switch-board 64 by a wire 103^f. Wire 103^c is connected to an outside terminal post on the upper end of the switch-board 64 by a wire 103^g and the wire 103^d is connected to the opposite outside terminal post on the upper end of the switch-board 64 by a wire 103^h. The intermediate 110 outside terminals of the switch-board 64 are connected by a wire 103ⁱ in which wire is interposed the motor 48 with its operative parts. The wires 104^a and 104^b are connected to a suitable source of energy such 115 as a city supply by wires 103 and 104 respectively.

The magnets 44 are connected in series by wires 105, 106, 107, and 108, the wire 106 being connected to an inner terminal on the 120 130

lower end of the switch-board 64 by a wire 106^a, and the wire 105 being connected to an inner terminal post on the lower end of the switch-board 64 by a wire 105^a. The 5 wire 107 is connected to an inner terminal on the upper end of the switch-board 64 by wire 107^a, and the wire 108 is connected to an inner terminal on the upper end of the switch-board 64 by wire 108^a. A battery 115 10 is connected to the two inner terminals intermediate the ends of the switch-board 64 by wires 105^b and 106^b.

When the arm 21 in the switch-box shown to the right in Fig. 15 of the drawings is 15 oscillated in an anti-clockwise direction by a moving train, the switch blades in the switch-board 64 are in engagement with the terminals on the lower end of such switch-board. The movement of arm 21 establishes 20 a circuit beginning at the supply wire 103 and extending through wire 104^a, to the innermost blade of the switch 24, through contact 34', wires 103^a, 103^c, wire 103^b and motor, 103^c, 103^b, contact 36', wire 25 104^b and out through wire 104. Simultaneously with the establishment of the motor circuit, a circuit is established through the appropriate magnets 44 as follows,—from the battery 115 through wires 106^b, 106^a, 108, 30 contact 35', to magnets, returning through 105, 105^a, 105^b, to battery 115. In this manner the bar 37 is held down against the tension of the springs 42, thereby securing 35 the switch in the housing 49 in such a position as to maintain the closed circuits already mentioned. The motor having been set in operation through this method, will continue to operate until the member 97 comes into engagement with the members 40 111 and 98, when the circuit connected with said motor will be broken. This operation takes effect before the gear 57 comes into engagement with the gear wheel 60, but the momentum of the machinery will carry this 45 gear wheel 54 around so that the gear 57 will come into engagement with the gear wheel 60 and cause the said gear 60 to rotate one-half turn. This will open the switch at the lower end of the switch blades and close 50 the switch at the upper end, at the same time turning the valve 74 and exhausting the air from the exhaust valve 91, as already described, and breaking the magnet circuit and releasing the bar 37. This will leave the 55 gate in a lowered position, with the switch, which is mounted on the frame 47, closed through the upper ends of the knife blades. When the arm 21 in the opposite housing 19 is oscillated in an anti-clockwise direction 60 the motor circuit is established as follows,—beginning at wire 103, through 104^a, to switch, to contact 31', through 103^c, 103^a, 103^b, 103^a, 103^b, contact 33', 104^b, and out at 104; and the magnet circuit is established 65 through wires 105^b, 107^a, 107, contact 32', to

magnets, back through wires 108, 108^a, 106^b, to battery 115. The motor having been set in operation, the machinery will co-operate as in the previous operation, with the result that the gate 88 will be raised and the different elements will be restored to their normal position, which is shown in Fig. 2.

It is thus seen that upon the passing of a train along the rail 22, the arm 21 will be oscillated, thereby closing the circuit 75 through the motor 48. The magnetic coils being energized, this arm will be retained in its downwardly moved position until the circuit through the magnetic coils is broken by means of the co-operating machinery 80 which is mounted on frame 47. It is also seen that the train, in passing along the rail and striking the arm 21, will lower the gate.

The next electrical device with which the train comes into contact is stationed at the 85 opposite side of the gate, and the arm 21 is oscillated in an opposite direction relatively to the co-operating parts, which are secured in the housing 19. This will result in again closing the circuit and operating 90 the machinery to raise the gate, as already described. It is thus seen that there is provided in this device, automatic means for lowering a gate at a railroad crossing upon the approach of a train, and automatic 95 means for raising the gate after the train has passed the crossing.

It is also clear that this device is adapted to raise and lower the gate as described, irrespective of which direction the train is 100 going in, so that the device may be used on a double-track railroad as well as on a single-track railroad. In a double-track railroad of course, the electrical devices would have to be stationed at opposite sides of the railroad track at points on opposite sides of the 105 gate, as will be readily understood.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations 115 and modifications as come within the scope of the appended claims.

Having described my invention, what I claim as new and desire to secure by Letters Patent is:—

1. A railroad crossing gate operated by compressed air mechanism; an electric motor for operating said compressed air mechanism; means spaced along the railroad track for automatically setting said 125 motor in operation; gears operable by said motor; a cam on one of said gears for automatically stopping said motor, substantially as described.

2. In combination with a railroad cross-

- ing gate adapted to be lowered and raised by compressed air mechanism, an electric motor adapted to operate said compressed air mechanism; electrical devices stationed 5 along the railroad track on opposite sides of said gate; an electric circuit connecting each of said elements with said motor; gears operable by said motor; a cam on one of said gears for stopping said motor; and 10 a switch operable by a segment on one of said gears for partly re-establishing said circuits.
3. In combination with a railroad crossing gate adapted to be lowered and raised 15 by compressed air mechanism, an electric motor adapted to operate said compressed air mechanism; electrical devices stationed along the railroad track on opposite sides of said gate; an electric circuit connecting each 20 of said devices with said motor; a rocker arm mounted in each of said devices; resilient contacts connected to each of said devices adapted to be closed by said rocker arm; and gears on said motor for automatically 25 breaking said circuit, substantially as described.
4. In combination with a railroad crossing gate adapted to be lowered and raised by compressed air mechanism, an electric motor adapted to operate said compressed air mechanism; electrical devices stationed 30 along the railroad track on opposite sides of said gate; an electric circuit connecting said devices with said motor; contacts connected 35 on each of said devices for closing said circuit; an upwardly projecting arm adjacent the rail of said railroad track and adapted, upon the passing of a train over said rail at said point, to operate said circuit contacts; and gears on said motor for automatically 40 breaking said circuit, substantially as described.
5. In combination with a railroad crossing gate adapted to be lowered and raised 45 by compressed air mechanism, an electric motor adapted to operate said compressed air mechanism; electrical devices stationed along the railroad track on opposite sides of said gate, comprising a knife blade switch 50 and magnets; an electric circuit connecting said switch and said motor; a rocker arm in each of said electrical devices adapted to close the switches therein; a transverse bar secured to said rocker arm and adapted to engage said magnets to hold said switch closed; and gears on said motor adapted to release said rocker arm and break said 55 circuits.
6. In combination with a railroad crossing gate adapted to be lowered and raised 60 by compressed air mechanism, an electric motor adapted to operate said compressed air mechanism; an electric circuit connecting with said motor; a switch interposed in 65 said circuit at points on opposite sides of
- said gate; an eccentric gear operable by said motor for opening and closing said switch; and a cam operable by said motor for breaking said circuit, substantially as described. 7. In combination with a railroad crossing gate adapted to be lowered and raised by compressed air mechanism, an electric motor adapted to operate said compressed air mechanism; an electric circuit connecting with said motor; a switch interposed in 70 said circuit at points on opposite sides of said gate; an arm connected with said switch and adapted, upon the passing of a train along the rail at said point, to close said switch; a bar on said arm and movable therewith means for retaining said switch in closed position; and a cam operable by 75 said motor for breaking said circuit, substantially as described.
8. In combination with a railroad crossing gate adapted to be lowered and raised by compressed air mechanism, an electric motor adapted to operate said compressed air mechanism; an electric circuit connecting with said motor; a switch interposed in 80 said circuit at points on opposite sides of said gate; a rocker arm connected with said switch and adapted, upon the passing of a train along the rail at said point, to close said switch; a bar secured to said arm and movable therewith; magnets adapted, when energized, to retain said bar in closed position; and a cam operable by said motor for breaking said circuit, substantially as described. 90
9. In combination with a railroad crossing gate adapted to be lowered and raised by compressed air mechanism, an electric motor; means connected with said motor and adapted, upon the operation of said motor, to raise and lower said gate; an electric circuit connecting with said motor; a switch interposed in 95 said circuit at points on opposite sides of said gate; a rocker arm connected with said switch and adapted, upon the passing of a train along the rail at said point, to close said switch; a bar secured to said arm and movable therewith; magnets engaging said bar for retaining said switch in closed position; and a cam operable by said motor for breaking said circuit, substantially as described. 100
10. In combination with a railroad crossing gate adapted to be lowered and raised by compressed air mechanism, an electric motor; means connected with said motor adapted, upon the operation of said motor, to raise and lower said gate; a gear wheel co-operating with said motor; a segmental gear secured to the periphery of said gear wheel; and an eccentric gear operated by said segmental gear adapted to actuate a valve and a switch, substantially as described. 120
11. In combination with a railroad cross- 125

ing gate adapted to be lowered and raised by compressed air mechanism, an electric motor; gears connected with said motor adapted, in one position, to raise said gate and adapted, in another position, to lower said gate; and gears on said motor for automatically regulating said gate raising means for alternately lowering and raising said gate, substantially as described.

10 12. In combination with a railroad crossing gate adapted to be lowered and raised by compressed air mechanism, an electric motor; means connected with said motor for alternately lowering and raising said gate; an electric circuit connecting with said motor; a switch interposed in said circuit; a valve regulating the flow of air to said compressed air mechanism; and gears operable by said motor for automatically and 15 synchronously opening and closing said valve and for operating said switch, substantially as described.

13. In combination with a railroad crossing gate adapted to be lowered and raised by compressed air mechanism, an electric 25 motor; means connected with said motor for alternately lowering and raising said gate; an electric circuit connecting with said motor; a switch interposed in said circuit; a valve regulating the flow of air to said compressed air mechanism; a feed pipe communicating with said valve; an exhaust valve communicating with said feed pipe; and eccentric gears on said motor for automatically operating said valves and said 30 switch synchronously, substantially as described.

In testimony whereof I have signed my name to this specification in the presence of two subscribing witnesses.

JOHN R. GOLDEN.
